ASH TRAY

James A. McClure, 1025 Sharon Road,
Santa Ana, Calif. 92706

Filed Mar. 10, 1975, Ser. No. 556,823

Term of patent 14 years

Int. Cl. D27—03

U.S. Cl. D27—27

Fig. 1

Fig. 2

FIG. 1 is a top plan view of an ash try showing my new design;

FIG. 2 is a side elevational view thereof; and,
FIG. 3 is a bottom plan view thereof.

I claim:

The ornamental design for an ash tray, substantially as shown.
